UNITED STATES PATENT OFFICE.

JOHN LANGENEGGER, OF WEST NEW YORK, NEW JERSEY, ASSIGNOR TO BLANCK & CO., INC., OF NEW YORK, N. Y.

DESIGN FOR EMBROIDERED LACE.

Application filed December 29, 1924. Serial No. 11,819. Term of patent 3½ years.

To all whom it may concern:

Be it known that I, JOHN LANGENEGGER, a citizen of the United States, and resident of West New York, county of Hudson, State of New Jersey, have invented a new, original, and ornamental Design for Embroidered Lace, of which the following is a specification, reference being had to the accompanying drawing, forming a part thereof.

The figure is a plan view of embroidered lace showing my new design.

I claim:

The ornamental design for embroidered lace as shown.

In testimony whereof I affix my signature.

JOHN LANGENEGGER.
